UNITED STATES PATENT OFFICE.

HENRY SIEBEN, OF KANSAS CITY, MISSOURI.

DRIER.

Application filed November 16, 1925. Serial No. 69,326.

My invention relates to driers and more particularly to one for use in laundries, either commercial or private, for drying clothes, the present invention being an improvement on the driers illustrated in my United States Letters Patent No. 1,446,994 and 1,548,218, the principal object of the present invention being to provide a more efficient heating and circulation of the air whereby the drying effect is produced.

In accomplishing this object I provide improved details of structure, the preferred forms of which are illustrated in the accompanying drawings wherein:

Fig. 1 is a perspective view of a drier embodying my improvements, parts being broken away for better illustration.

Fig. 2 is a vertical section of the drier, arrows indicating the path of the air.

Fig. 3 is an enlarged detail perspective view of part of the drier, particularly illustrating the air jacket and the deflectors directing air from the jacket into the top of the drier.

Referring more in detail to the drawings, 1 designates a housing of any suitable size and material, but preferably constructed of rust-proof metal having the lower portion of its front permanently closed by a panel 2 and the upper portion having side guides 3 slidably mounting a door 4, which, when in functional position, closes an opening 5 embracing the upper half of the front of the housing, and is adapted for lowering in the guides to expose the opening when articles are to be inserted into or removed from the housing. The door is hung on ropes 6 run over pulleys 7 and 8 at the upper corners of the housing and connected with weights 9 that are adapted for vertical movement in casings 10 at the rear corners of the housing.

The door is provided with a handle bar 11 by which it may be manipulated and has an opening 12 normally closed by a hinged cover 13 which may be raised to permit observation of the contents of the drier.

The top of the housing is provided with ports 14 arranged in transverse rows, through which air may be delivered into the top of the drying chamber, and one end of the housing with ports 15 through which air may be delivered into the body of the chamber, as presently described, a row of ports 16 being located in the end wall adjacent the bottom of the housing. The

ports 14 and 15 are unobstructed, but the ports 16 are provided with a flat valve 17, hingedly mounted on the inner face of the end wall to hang over the ports 16 and close the same except under the operating conditions presently described.

Located over the top of the housing and extending down over the ends thereof is a jacket 18 preferably of sheet metal, bent to form a top and sides with the edges of the sides turned inwardly to form the supporting flanges 19 of sufficient width to support the jacket without obstructing any of the ports in the housing walls, the jacket being spaced from the housing wall to form a conduit through which heated air may be conducted to the several parts.

At one end of the housing the conduit is enlarged to house a gas burner 20 of any suitable construction and preferably supported within the conduit by a pipe 21 which extends through the end of the conduit and connects with a supply pipe 22, having a control valve 23. The gas burner is directly enclosed within a casing 24 formed of sheet metal bent to U-shape and secured to the ends of the conduit by welding or otherwise, the walls of the casing being spaced from the walls of the conduit to form air passages 25 at the front and back of the burner, and the bottom of the casing being provided with perforations 26 through which combustion supporting air may pass.

In the upper end of the combustion chamber portion of the conduit is a vent opening 27 surrounded by a flange 28 carrying a damper cap 29, whereby exhaust of gases from the burner may be controlled.

The conduit extends over the end of the housing opposite the combustion chamber to near the bottom of the housing in order to confine flow of air about the housing and direct it to the apertures 15.

Attached to the top of the housing, within the conduit and extending transversely thereacross, adjacent rows of the apertures 14 are baffle plates 30, preferably formed of sheet metal, the flanges 31 of which lie against the top of the housing and are secured thereto by rivets 32, the bodies of the plates being forwardly inclined to trap air passing through the conduit and direct it through the apertures 14 into the drying chamber.

While the gas burner may heat the air to the desired temperature, I prefer to sup-

plement this heating effect by electrical heaters arranged locally relative to the baffle plates so that heating of the air as it enters the top of the drying chamber may be assured. A preferred form of such electrical heaters comprises a resistance bar 33 which is attached to the top of the housing and extended transversely thereover forwardly of the row of perforations 14 located directly in advance of a baffle plate. Connected with each of the resistance bars is a circuit wire 34, leading to a switch 35 mounted on the housing so that flow of current may be conveniently controlled. There may be any desired number of baffle plates and electric heaters employed in combination with the gas burner to secure an even distribution of heated air to the top of the drying chamber. In order to effect such distribution I preferably graduate the height of the baffle plates, the first plate in train projecting but slightly into the conduit in order to intercept a small part of the air volume, the succeeding baffle being higher, and the last baffle in train leaving but a narrow channel for the passage of air into the vertical portion of the conduit.

The lower corner of the housing opposite the row of apertures 16 is divided off by a partition 36 forming a compartment 37 for an air blower 38 which may constitute an ordinary electric fan but which is arranged to draw air through openings 39 in the lower portion of the partition 36 and exhaust it through an opening 40 in the end of the housing. The openings 39 in the partition are made variable as to area by damper plate 41 slideable on the partition 36 and the exhaust opening 40 is covered by a screen 42 serving as a guard for the fan. The fan may be supplied with current through circuit wires 43 leading from the switch 35 as an ordinary cord and current may be supplied for the electric heaters and fan through wires 44 having a plug 45 that may be connected to a house wiring system through an ordinary wall socket.

While the housing chamber may be equipped with any suitable means for supporting articles to be dried, I prefer to equip it with a rack comprising the inclined end bars 46 having notches 47 for carrying the cross bars 48, as with this arrangement the cross bars may be easily and quickly positioned on the rails and only a sufficient number need be employed for carrying the articles to be dried.

I also preferably provide the drier with a disinfectant holder 49 which may be in any suitable form, and with a lamp 50 which may be connected in the circuit with the heaters and blower.

Assuming the drier to be constructed and assembled as described, the gas burner ignited and current supplied to the electric

heaters and to the blower, air passing up through the open intake end of the jacket conduit supports combustion for the gas burner, heating the air within the conduit so that the air tends to rise and flow in the upper horizontal portion, thereby drawing fresh air through the passageways 25 at the sides of the burner housing to further support combustion and provide a volume for drying purposes.

As the air is driven forwardly in the direction of the arrows, some of it comes in contact with the first baffle plate and is diverted downwardly through apertures in the top of the housing into the drying chamber, this portion of the air being directed over the first electrical heater so that its temperature is raised at the point of intake to the drying chamber. The balance of the air moves forwardly in the conduit to the next baffle plate where another portion is intercepted, heated by the adjacent electrical heater and diverted into the drying chamber, the balance of the air passing on to the last baffle where the same operation is repeated on some of the remaining air. The balance of the air is forced downwardly through the portion of the conduit at the end of the housing opposite the gas burner and finally escapes into the drying chamber.

Simultaneously with this operation, the fan draws air through the damper openings in the partition 36, creating a suction within the lower portion of the drying chamber, which is sufficient to open the flap valve 17 and expose the ports 16 to incoming air. This bottom flow of air, being cool, is held to the bottom of the housing and, being fresh, absorbs moisture that is drawn out of the articles supported on the rack so that saturation of the air in the chamber is avoided.

It is apparent that with the construction described, a thermo-siphonic effect is produced in the conduit, which promotes circulation of the heated air and that expansion of the air and mechanical deflection by the baffle plates will insure diversion of part of the air from the conduit into the top of the heating chamber and flow of the balance through the conduit and eventually into the drying chamber through the side ports, so that articles suspended on the rack are subjected to both a downward and upward flow of heated air which eventually all escapes from the chamber through the outlet opening 40, the moisture saturated air passing downwardly through the up-flowing volume of heated air.

It is apparent that by my arrangement of supply exhaust of heated air to and from the heating chamber and positive circulation of the air through and about the clothes, moisture is extracted from the clothes so that

the drying is effected by said current of air carrying the moisture away from the fabric.

While I have described my drier as adapted for laundry use, I do not wish to so limit the invention, as the drier may be employed as a dehydrator for fruits and vegetables and for other purposes.

What I claim and desire to secure by Letters Patent is:—

- 10 1. In a drier, a housing, a jacket enclosing portions of the housing and forming a conduit thereabout, and means for heating air within the conduit, the housing having ports communicating its interior with said conduit.
- 15 2. In a drier, a housing, a jacket enclosing portions of the housing and forming a conduit thereabout, means for heating air within the conduit, the housing having ports communicating with said conduit, and means in said conduit for deflecting air through said ports.
- 20 3. In a drier, a housing, a jacket enclosing portions of the housing and forming a conduit thereabout, means for heating air within the conduit, the housing having ports communicating with said conduit, means in

said conduit for deflecting air through said ports, and other heating means local to said deflecting means.

30

4. In a drier, a housing, a jacket forming a conduit exterior to the housing, the housing having transverse rows of ports communicating its interior with said conduit, and transverse baffles in said conduit, each 35 rearward of a row of ports.

5. In a drier, a housing, a jacket forming a conduit exterior to the housing, the housing having transverse rows of ports communicating its interior with said conduit, 40 and a series of baffles of gradually increasing heights, arranged transversely in said conduit, each rearward of a row of ports.

6. In a drier, a housing, a jacket on the top wall and portions of the end walls of the 45 housing forming an exterior conduit, open at one end and closed at the other end, the housing having ports communicating its chamber with the conduit, a heater in the open end of the conduit, and means for 50 maintaining a circulation of air through the conduit and housing chamber.

In testimony whereof I affix my signature.
HENRY SIEBEN
